1 Claim

ABSTRACT OF THE DISCLOSURE

A propeller of the marine screw type having a main blade and an auxiliary blade located at the discharge end of the main blade, said blades having a slot running therebetween at the trailing edge of the main propeller blade. The width of the slot in cross sectional area reduces its size from the pressure side of the blade towards the suction side of the blade to create a throttle effect resulting in an increase in water flow velocity through the slot and a reduction of the pressure in the suction side of the propeller. The structure so presented reduces cavitation and improves performance of the propeller by reducing turbulence on the suction side of the propeller blade.

This invention relates to propellers, particularly marine screws, but also propellers for fans and the like, having two or more blades.

The primary object of the invention is to provide a propeller having a high efficiency, and more particularly the invention relates to a propeller wherein the main blade is provided with an auxiliary blade located at the discharge edge of the main blade when going forward, and the novel features according to the present invention consist in the following: that in an arbitrary axis parallel cylinder section through the blades the pitch on the blades is defined by helical lines through the terminal points of the longitudinal center lines of these sections, and that the helical lines through the terminal points of the cylinder sections of the auxiliary blade at the same radius have the same or a larger pitch than the helical lines of the main blade, and that the helical lines of the auxiliary blade are located abaft of the helical lines of the main blade relative to the forward speed of the vessel.

The number of such pair of blades (main and auxiliary blade) may vary from two to any proper number.

The slot between the main blade and the auxiliary blade serves the following purpose: When the propeller rotates, water (air, gas or the like) will be urged in the direction of rotation along the pressure side of the main blade and through the slot, which according to the equation of Bernoulli create an under-diminished pressure at the discharge edge of the main blade, whereby the water flow at the suction side of the main blade is prevented from loosing. Thereby the common undesired turbulence on the suction side of the propeller blade is avoided.

The area of the auxiliary blade is maximum half of the area of the main blade.

The main blade and the auxiliary blade may be formed in one single piece, the blades being separated by a slot sloping astern and being limited by a portion of the pressure side of the main blade at its discharge edge and a portion of the suction side of the auxiliary blade at its inlet edge, when the vessel is going forward, corresponding to the direction of flow of the water.

In some instances it may be advantageous to arrange the main blade and the auxiliary blade with a forwardly directed "cast," and the auxiliary blade may be revolving.

The propeller according to the invention will be further described by way of example in connection with the accompanying drawings, in which:

FIG. 1 illustrates the propeller, seen in the forward direction of the vessel, i.e. from the end of the hub;

FIG. 2 is a displayed cylinder section along line II-II

2

in FIG. 1, illustrating a main blade and an auxiliary blade, and indicating the pitch's helical lines β and α , respectively;

FIG. 3 is a longitudinal sectional view through the hub and the pair of blades along the lines IIIa-IIIa and IIIb-IIIb in FIG. 1;

FIG. 4 is a view similar to FIG. 2, but illustrating a modified embodiment, in which the main blade and the auxiliary blade is made in one single piece.

In the drawings the reference letter *f* (FIGS. 1 and 2) indicates the forward direction of the vessel, while *d* is indicating the rotation direction of the propeller.

Each of the two blades (main blades) 1 of a propeller is provided with an auxiliary blade 2 located at the discharge edge of the associated main blade 1, assuming the vessel is moving forward. In an arbitrary axis parallel cylinder section, e.g. II-II in FIG. 1, through the propeller blades 1, 2 the pitch on the blades is defined by helical lines through the terminal points of these sections' longitudinal center lines. The helical lines through the terminal points of the cylinder sections of the auxiliary blade 2 (see FIG. 2) at the same radius have according to FIG. 2 a larger pitch than the helical lines of the main blade 1; this being illustrated on the drawing by the fact that α is larger than β .

The helical lines through the terminal points of the center line of the cylinder sections of the auxiliary blade 2 may at the same radius be equal to those of the main blade with respect to the pitch, confer FIG. 4 in which the main blade 1" and the auxiliary blade 2" are made in one single piece, a slot 4" being provided in order to separate the blades. A plate piece 5 is welded to the main blade 1" in order to overlap the auxiliary blade 2" at the slot opening.

The helical lines of the auxiliary blade are located abaft of the helical lines of the main blade 1 by forward motion of the vessel.

On the drawings the reference numeral 3 indicates the hub and 1' the inlet edge of the main blade by going forward. The slot between the main blade and the auxiliary blade is 4 and 4', respectively.

Preliminary experiments have shown that very good results were obtained when the slot 4 or 4' had a width in the axial direction of approximately 0.06-0.09 times that of the main blade by 0.6 of the radius of the main blade.

If desired, the auxiliary blade can be made revolving (not shown), which can be achieved by any of a number of known methods. In the shown embodiment the auxiliary blade 2, 2' and the main blade 1, 1" have "cast" forwardly (see FIG. 3).

What I claim is:

1. A propeller suitable for use as a marine screw having a hub and a main blade and an auxiliary blade on said hub, said main blade and said auxiliary blade both slope forwardly with respect to the forward direction of travel of a vessel propelled by said propeller, said auxiliary blade having a maximum of one-half the area of the main blade, said auxiliary blade being disposed adjacent the discharge end of the main blade and overlapping the trailing edge of the main blade with the pressure side of the main blade facing the suction side of the auxiliary blade, whereby a slot is formed between said auxiliary blade and the trailing edge of said main blade, the auxiliary blade and said main blade being so proportioned that the slot has a length of about 0.6 times the radius of the main blade and a width of 0.06 to 0.09 times the width of the main blade, and the pitch angle of said auxiliary blade being at least equal to the pitch angle of said main blade.
